UNITED STATES PATENT OFFICE.

ELIJAH H. PINNEY AND EVERLY A. JONES, OF CASS CITY, MICHIGAN.

ANIMAL-POKE.

SPECIFICATION forming part of Letters Patent No. 700,558, dated May 20, 1902.

Application filed January 27, 1902. Serial No. 91,430. (No model.)

To all whom it may concern:

Be it known that we, ELIJAH H. PINNEY and EVERLY A. JONES, citizens of the United States, residing at Cass City, in the county of 5 Tuscola and State of Michigan, have invented certain new and useful Improvements in Animal-Pokes, of which the following is a specification, reference being had therein to the accompanying drawings.

10 The invention relates to an animal-poke especially designed for rams, whereby when employed the separation of the latter from the ewes during certain seasons of the year is rendered unnecessary.

15 The invention consists in the peculiar construction of the animal-poke and in the novel arrangement and combination of the various parts thereof, as will be more fully hereinafter described, and pointed out in the claims.

20 In the drawings, Figure 1 is a perspective view of an embodiment of our invention. Figs. 2 and 3 are front and side elevations, respectively, of the animal-poke, showing the same as applied to an animal; and Fig. 4 is a 25 sectional elevation.

In the drawings thus briefly described the animal-poke is shown as consisting, essentially, of a supporting member adapted to be secured to the body of the animal and a poke 30 member pivoted to the supporting member and adapted to extend substantially intermediate of the fore legs. In construction the supporting member comprises a body-plate A, extending beneath the body of the animal, as indicated in Figs. 2 and 3, and secured to the body by suitable straps or bands. The forward end of the plate terminates in two upwardly-extending diverging arms B and C, each of which at its free end is apertured, as 35 at a, while the rear end of the plate carries laterally-extending lips E, the lips being also apertured. The plate is also curved to conform to the body of the animal and is secured in place by a neck-strap F, which is joined to the arm ends described, and a similar retaining or securing band G, connecting the laterally-extending ears and adapted to pass over the back of the animal. Intermediate of the plate ends and at a point substantially between the 40 fore legs of the animal the plate is provided with depending lips or bearings c and d, the bearings being formed, preferably, by a U-shaped plate e, which is attached to the under side of the body-plate by suitable securing devices, such as rivets f. Pivoted be-

tween these bearings is the poke member H, comprising the poke-bar proper, I, and the branching arms or prongs J, the prongs with the exception of the central arm, which is preferably straight, diverging, as illustrated, 60 forming a fan-shaped poke. As shown, the poke member is secured in place by a suitable bolt K, and the upper or inner end of the bar has a bearing-surface g formed thereon, which is adapted when the poke member is in a substantially vertically depending position to abut against the plate e, as illustrated in Figs. 3 and 4. By constructing the inner end of the poke in the manner indicated it will be obvious that it is free to swing in a forward 65 upwardly direction, but is held from rearward movement beyond its vertical position.

From the description of our invention it will be readily seen that the animal-poke is of simple and durable construction, which enables it to be manufactured at slight cost, and is so applied to the animal as to allow the latter to lie upon the ground as free as if the poke were not used.

What we claim as our invention is—

1. In an animal-poke, the combination with a curved metallic body-plate terminating at its forward end in integral upwardly-extending diverging arms, of a neckband adapted to be connected to the arm ends, a securing 85 band or strap for the rear end of the plate, and a depending poke member pivoted to the plate for free swinging movement in a forward direction.

2. In an animal-poke, the combination with an oblong metallic plate curved about its longitudinal axis to conform to the contour of the body of the animal, of diverging arms integral with the plate and extending upwardly from the forward end of the latter, a neckband connecting the arm ends, a securing band for the rear portion of the plate, a vertically-dependig poke-bar having pivotal connections with the plate and provided with diverging prongs or arms, and a bearing-surface formed on the inner end of said bar, substantially as and for the purpose set forth.

In testimony whereof we affix our signatures in presence of two witnesses.

ELIJAH H. PINNEY.
EVERLY A. JONES.
